UNITED STATES PATENT OFFICE.

VINCENT MARTELLI, OF REVERE, MASSACHUSETTS.

DESIGN FOR A SHOE.

Application filed July 10, 1923. Serial No. 6,748. Term of patent 7 years.

To all whom it may concern:

Be it known that I, VINCENT MARTELLI, a subject of the King of Italy, residing at Revere, in the county of Suffolk and Commonwealth of Massachusetts, have invented a new, original, and ornamental Design for a Shoe, of which the following is a specification, reference being had to the accompanying drawing, forming a part thereof.

The figure is a perspective view of a shoe showing my new, original and ornamental design.

I claim—

The ornamental design for a shoe as shown.

V. MARTELLI.
